CLAIM

The ornamental design for a device for killing mice, as shown and described.

DESCRIPTION

FIG. 1 is a perspective view of a device for killing mice showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear side perspective view thereof.

Any shading and cross-hatching are not features of the design but are utilized to illustrate the surface contours of the device for killing mice design in the drawings.

The broken lines in the drawings depict portions of the device for killing mice that form no part of the claimed design.
